DESIGN FOR A LADY'S HOSE OR SIMILAR ARTICLE

Philip Gerton, New York, N. Y.

Application December 11, 1936, Serial No. 66,479

Term of patent 14 years

To all whom it may concern:

Be it known that I, Philip Gerton, a citizen of the United States, residing in New York city, in the county of New York, in the State of New York, have invented a new, original, and ornamental Design for Lady's Hosiery or Similar Article, of which the following is a specification, reference being had to the accompanying drawing, forming part thereof:

Figure 1 is a side perspective view of a stocking showing my new design.

Figure 2 is a partial rear view of the same.

The dominant feature of the present invention resides in an open mesh portion which extends from the heel of the stocking into the ankle portion thereof in contrast with the closely knitted stocking leg portion.

I claim:

The ornamental design for a lady's hose or similar article, substantially as shown and described.

PHILIP GERTON.
